UNITED STATES PATENT OFFICE.

MARY L. W. MARTINOT, OF NEW YORK, N. Y.

HEATER.

SPECIFICATION forming part of Letters Patent No. 438,932, dated October 21, 1890.

Application filed June 16, 1890. Serial No. 355,631. (No model.)

To all whom it may concern:

Be it known that I, MARY L. W. MARTINOT, of New York city, in the county and State of New York, have invented a new and useful Improvement in Heaters, of which the following is a full, clear, and exact description.

My invention relates to an improved heater especially designed for use in connection with gas and similar burners, and has for its object to provide a device of simple and durable construction capable of use for heating water or other liquids or food and in heating the halls or apartments of buildings.

The invention consists in the novel construction and combination of the several parts, as will be hereinafter fully set forth, and pointed out in the claims.

Reference is to be had to the accompanying drawings, forming a part of this specification, in which similar figures and letters of reference indicate corresponding parts in all the views.

Figure 1 is a front elevation of the heater illustrated as applied to a gas-burner. Fig. 2 is a central vertical transverse section through the heater. Fig. 3 is a front elevation of the lower section of the burner, illustrating the said section as supporting a cup. Fig. 4 is a plan view of the lower section, and Fig. 5 is a bottom plan view of the same.

The heater is constructed, preferably, in two sections—namely, an upper section A and a lower section A'. The lower section A' consists of a burner 10, of any suitable or approved construction, adapted to receive gas from the burner 11 of the gas-bracket.

The burner of the heater, as illustrated, comprises a shell-like body provided at its bottom with a central opening 12 to receive the bracket-burner and with a series of air-apertures 13. The top 14 of the burner is constructed of gauze or equivalent material, and from the marginal edges of the top brackets 15 are projected upward and attached to the bottom of a table 16, which table is preferably semicircular in general contour, and the table is provided near its margin with an upwardly-extending and preferably continuous flange 17, the flange following the shape of the table, and the table is further provided with a central opening 17^a, registering, or

practically so, with the burner. The table at its rear or straight edge has formed integral therewith or attached to it a downwardly-extending shield 18, the said shield being 55 adapted to protect any adjacent wood-work, for instance, from the heat generated by the gas-flame at the top of the burner.

The upper section A comprises a drum 19, constructed of sheet-iron or other suitable material, and the cross-sectional contour of the drum corresponds to the general contour of the table of the lower section. The drum is made of sufficient size at its base to rest upon the table in contact with either the outer or 65 the inner face of the flange 17. In the front circular face of the drum 19 at or near the upper end thereof a horizontal slot or opening 20 is produced, which slot or opening is surrounded by a hood 21, which hood extends 70 outward at an angle to the drum, the upper and lower sides being flared in opposite directions, as is best illustrated in Figs. 1 and 2. A shield 22 is attached to the rear or straight face of the drum by means of brackets 23 or equivalent fastening devices, the functions of the said shield being the same as those of the lower shield 18.

For heating purposes the lower section is placed upon the burner of the gas-bracket 80 and the upper or drum section is placed in position upon the lower burner-section. The gas having been turned on and lighted at the gauze top of the burner, the heat ascends and finds an exit through the flaring hood 21, which 85 causes the heat to radiate therefrom some distance out into the room or passage to be heated, while the body of the drum itself also gives off a quantity of heat.

If the device is to be used for heating 90 liquids, foods, &c., the upper section is removed and a cup 24 or other receptacle corresponding in contour to the space within the table-flange 17 is placed upon the said table, as shown in Fig. 3. In addition to the support from the gas-bracket burner, the device may be further supported if the burner is near the wall by attaching the upper shield 95 22 to the wall.

Having thus described my invention, I 100 claim as new and desire to secure by Letters Patent—

1. As an improved article of manufacture, a heater constructed in two detachable sections, the lower section consisting of a burner and a table supported above the burner and the upper section of a drum adapted to rest upon the table and provided with an opening in one face surrounded by an outwardly-flaring hood, substantially as shown and described.

2. In a heater, the combination, with a lower section consisting of a burner and a flanged table supported above the burner, of an upper section comprising a hood adapted to rest upon the table in engagement with the flange and provided with an opening in its outer face and an outwardly-flaring hood surrounding the said opening, substantially as and for the purpose set forth.

3. In a heater, the combination, with a lower section comprising a burner, a table supported above the burner, having an opening registering with the burner, a flange surrounding the said opening, and a shield projected down-

ward from one marginal edge of the table, of an upper section consisting of a drum conforming in cross-section to the contour of the table-flange and provided in its front face with an opening, an outwardly-flaring hood surrounding the opening of the drum, and a shield attached to the rear of the drum, substantially as and for the purpose specified.

4. In a heater, the combination, with the burner, of a table supported above the burner and provided with an opening therein, a shield projected downward from the table at one side of the burner, and an upwardly-extending flange secured to the upper face of the table surrounding the opening therein, whereby a chamber is formed for the reception of a drum or other vessel, as specified.

MARY L. W. MARTINOT.
